UNITED STATES PATENT OFFICE

121,949

DESIGN FOR A STORAGE BATTERY VENT PLUG

Oswald B. Carson, Bronxville, N. Y., assignor to
American Hard Rubber Company, New York,
N. Y.

Application June 19, 1940, Serial No. 93,095

Term of patent 7 years

To all whom it may concern:

Be it known that I, Oswald B. Carson, a citizen of the United States and a resident of Bronxville, in the county of Westchester and State of New York, have invented a new, original, and ornamental Design for a Storage Battery Vent Plug, of which the following is a specification, reference being had to the accompanying drawing, forming a part thereof, and in which:

Fig. 1 is a plan view of a storage battery vent plug, showing my new design; Fig. 2 is a side elevational view in direction of arrow 2 in Fig. 1; Fig. 3 is a side elevational view in direction of arrow 3 in Fig. 1.

I claim:

The ornamental design for a storage battery vent plug, as shown.

OSWALD B. CARSON.
